UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed April 30, 1924. Serial No. 709,977.

To all whom it may concern:

Be it known that I, CHARLES DAVID BONSALL, a citizen of the United States, and a resident of the city of Pittsburgh, in the 5 county of Allegheny and State of Pennsylvania, have invented a certain new and useful Improvement in Car Roofs, of which the following is a specification.

This invention relates to car roofs of the 10 all-steel riveted-up type wherein self supporting roof sheets extend from side plate to side plate of the car and are formed along their side margins with raised portions that are rigidly secured together to form hollow 15 weather proofing seams or joints that serve as ventilating flues and function as carlines.

One of the principal objects of the present 20 invention is to increase the strength and rigidity of the roof by improving the sectional shape and arrangement of the lapped portions of adjacent sheets. Another object is to utilize the seams or joints as ventilating flues. Another object is to prevent water that may enter the seams or joints 25 from reaching the interior of the car. Other objects are to simplify the construction of the roof and to cheapen the cost thereof.

The invention consists principally in shaping and arranging the cooperating marginal 30 portions of the roof sheets to form hollow weather proofing seams or joints that are better fitted for taking care of contemplated stresses; it also consists in strengthening said joints by means of a member that serves 35 as a drain channel for carrying off any water that may enter said joints; and it also consists in the parts and in the arrangements and combinations of parts hereinafter described and claimed.

40 In the accompanying drawing, which forms part of this specification, and wherein like symbols refer to like parts wherever they occur.

Fig. 1 is a plan view of a portion of the 45 car roof comprising my invention,

Fig. 2 is an enlarged transverse section through one-half of the car roof on the line 2-2 in Fig. 1,

Fig. 3 is a cross section through one of 50 the hollow seams at the ridge on the line 3-3 in Fig. 1,

Fig. 4 is a similar section taken midway of the ridge and eaves on the line 4-4 in Fig. 1,

Fig. 5 is a similar section taken at the side 55 plate on the line 5-5 in Fig. 1, and

Fig. 6 is a cross section through the eaves portion of the roof, the section being taken through one of the hollow seams on the line 2-2 in Fig. 1.

The roof shown in the accompanying drawing comprises metallic roof sheets 7 that extend transversely of the car from eaves to eaves thereof with their side margins overlapping. The roof sheets slope 60 upwardly from the eaves to the ridge and are supported at their eaves ends on metal side plates 8. The roof sheets are rigidly secured to the side plates by rivets 9 and are provided with depending eaves flanges 10 which overhang the outer edges of the side plates.

Each roof sheet is pressed from a sheet blank of uniform width and has its side margins pressed up and positively secured 75 to a similar margin of an adjacent sheet to form hollow weather proofing seams or joints A that extend from side to side of the car and function as carlines to increase the load carrying capacity of the roof and to 80 brace and stiffen the car body. The eaves ends portions of the hollow seams A are turned down over the side plate and their 85 ends left open. The downwardly opening eaves ends of the hollow seams A permit ventilation of the car while preventing rain from entering the same.

As shown in the accompanying drawing, the hollow ribs or carlines A are of uniform 90 width from eaves to eaves and have a maximum depth at the ridge and gradually decrease in depth towards the eaves where they are turned down over the side plates to form the ventilating flues. The hollow 95 seams A are of substantially inverted channel-shaped section at the ridge; and on opposite sides of the ridge each seam is provided at its top with a channel B which has a depth at the eaves ends of the sheet corresponding to the depth of said seam and gradually decreases in depth to the ridge 100 where it merges into the plane of the top of said seam. Thus, the hollow seams A gradually change from a single inverted channel section at the ridge to a section at 105 the eaves comprising two low and narrow inverted channels C that are separated by the upwardly opening channel B. The in-

verted channels C, together with the upwardly opening channels B, are turned down over the side plate and thus form double ventilating flues at each end of the seam.

5 The side marginal portion of each roof sheet 7 is raised above the body of the sheet in the form of a seam flange of uniform width which changes from a high inverted L-shaped section at the ridge to a low inverted channel-shaped section at the eaves whose outer wall is provided with a laterally extending base flange located substantially in the plane of the body of the sheet; that is, said pressed up marginal portion has 10 a nearly vertical web portion 11 at the top of which is an outwardly projecting flange 12 whose outer portion 13 is depressed or offset downwardly on each side of the ridge an amount or distance that gradually increases towards the eaves where the downwardly offset flange 13 lies in the plane of the body of the sheet. By reason of the sheet being pressed from a sheet blank of uniform width, the gradually decreasing 15 depth of the web portion 11 of each seam flange from ridge to eaves affords surplus metal which is utilized in gradually increasing from ridge to eaves the extent of the offsetting of the downwardly offset marginal 20 flange 13 of said seam flange. Therefore, as the depth of the webs 11 decreases from ridge to eaves, there is a corresponding increase from ridge to eaves in the depth of the web 14 that connects the top flange 12 25 with the depressed outer marginal flange 13. 30 with the result that said depressed marginal flange 13 has a greater inclination than the top of the seam flange and reaches the plane 35 of the body of the sheet adjacent to the 40 eaves ends thereof.

The sheets are assembled by lapping the depressed outer marginal portions 13 of the seam flanges of adjacent sheets. The lapped depressed marginal portions are then rigidly secured together by rows of rivets 15. When thus assembled, the lapped seam flanges cooperate to form the hollow seams or joints A, which gradually change from an inverted channel-shaped section at the 45 ridge to a section at the eaves comprising the central upwardly opening channel B having the inverted channels C located on each side thereof.

The hollow seams A are also provided 55 with combined strengthening members and drain channels or conductors 16. Each of these members is pressed from a sheet of uniform width and comprises a wide and flat section at the ridge which gradually 60 changes to a narrow channel-shaped section at the eaves. The upstanding side flanges 17 of the combined strengthening and trough members are located within the inverted channels C and increase in depth 65 from ridge to eaves an amount correspond-

ing to the extent of the offsetting of the downwardly offset portions 13 of the seam flanges. The eaves ends portions of the members 16 rest on and are rigidly secured to the tops of the side plates 8 by means of 70 the endmost rivets in the row of rivets 15 that rigidly secure the lapped seam flanges together. The members 16 slope upwardly from ridge to eaves at an angle corresponding to the slope of the depressed marginal 75 portions of the lapped seam flanges and are secured flatwise to said depressed marginal flanges by means of the rivets 15 that secure 80 said flanges together. It is noted that the members 16 serve to increase the strength and rigidity of the joints and serve also as drain troughs for carrying away any water that may enter the joints of the seams.

It is also noted that the seam or joint construction produced by the cooperating seam flanges of adjacent sheets accomplish the various functions of the carline. The sectional shape of the seams at the ridge serves to take care of the vertical roof load, and the cross sectional shape of the seams at the 90 eaves serves to take care of the stresses that tend to rack and twist the car body and distort it endwise. This increased strength and rigidity of the seams enables a roof to be produced that will be stiffer and stronger 95 than previous roofs of the same weight of metal. It is also noted that the seam construction provides a trough for carrying away any water that may enter the joints of the 100 seams by reason of improper riveting or defective sheets.

The invention is not limited to the precise shapes and arrangements of parts shown and described.

What I claim is:

1. A car roof comprising metal roof sheets having upwardly offset side marginal portions that are lapped for a portion of their width and positively secured together to form hollow upstanding seams whose cross 110 sectional shape changes from an inverted channel section at the ridge into a section at the eaves comprising two inverted channels that are separated by an upwardly opening channel of a width corresponding substantially to that of the sheet lap. 115

2. A car roof comprising roof sheets extending from eaves to eaves and having their adjacent side marginal portions shaped and positively secured together to form hollow 120 upstanding seams whose cross sectional shape changes from an inverted channel at the ridge into two horizontally spaced inverted channels at the eaves that are turned down over the side of the car and left open to provide for ventilation. 125

3. A car roof comprising metal roof sheets extending from eaves to eaves of the car, the side marginal portions of adjacent sheets being lapped and positively secured together 130

to form hollow upstanding weather proofing seams, each of said seams having a channel formed in its top that extends longitudinally thereof, the extent of the sheet lap being less than the width of the seams.

4. A car roof comprising metal roof sheets extending from eaves to eaves of the car, the side marginal portions of adjacent sheets being lapped and positively secured together to form hollow upstanding weather proofing seams that are turned down at the eaves and left open to provide for ventilation, each of said seams having a channel formed in its top that extends longitudinally thereof, the width of said channel corresponding substantially to the width of the sheet lap.

5. A car roof comprising metal roof sheets extending from eaves to eaves of the car, the side marginal portions of adjacent sheets being lapped and positively secured together to form hollow upstanding weather proofing seams, each of said seams having a channel formed in its top that extends longitudinally thereof and increases in depth from ridge to eaves, the width of said channel corresponding substantially to the width of the sheet lap.

6. A car roof comprising metal roof sheets extending from eaves to eaves of the car, the side marginal portions of adjacent sheets being lapped and positively secured together to form hollow upstanding weather proofing seams, each of said seams having a channel formed in its top that extends longitudinally thereof and increases in depth from ridge to eaves, and a stiffening member located in said hollow seams, said stiffening member being of greater width than the width of the sheet lap and being secured to the car at the eaves and to the seam at points intermediate the eaves.

7. A car roof comprising metal roof sheets extending from eaves to eaves of the car, the side marginal portions of adjacent sheets being lapped and positively secured together to form hollow upstanding weather proofing seams, each of said seams having a channel formed in its top that extends longitudinally thereof and increases in depth from ridge to eaves where its depth corresponds substantially to the depth of said seam, the width of said channel corresponding substantially to the width of the sheet lap.

8. A car roof comprising roof sheets having their adjacent side marginal portions offset upwardly, the upwardly offset side marginal portions of adjacent sheets being lapped for a portion of their width and positively secured together to form hollow upstanding seams, the lapped portions of adjacent sheets being less than the width of the seam and being offset downwardly to form channels in said seams that extend longitudinally thereof.

9. A car roof comprising roof sheets extending from eaves to eaves and having their adjacent side marginal portions offset upwardly, the upwardly offset side marginal portions of adjacent sheets being lapped for a portion of their width and positively secured together to form hollow upstanding seams that extend from eaves to eaves of the car, the lapped portions of adjacent sheets being less than the width of the seam and being offset downwardly on opposite sides of the ridge to form channels in said seams that extend longitudinally thereof.

10. A car roof comprising roof sheets extending from eaves to eaves and having their adjacent side marginal portions offset upwardly, the upwardly offset side marginal portions of adjacent sheets being lapped for a portion of their width and positively secured together to form hollow upstanding seams that extend from eaves to eaves of the car, the lapped portions of adjacent sheets being less than the width of the seam and being offset downwardly on opposite sides of the ridge to form channels in said seams that extend longitudinally thereof, said channels increasing in depth from ridge to eaves.

11. A car roof comprising roof sheets extending from eaves to eaves and having their adjacent side marginal portions offset upwardly, the upwardly offset side marginal portions of adjacent sheets being lapped for a portion of their width and positively secured together to form hollow upstanding seams that extend from eaves to eaves of the car, the lapped portions of adjacent sheets being less than the width of the seam and being offset downwardly on opposite sides of the ridge to form channels in said seams that extend longitudinally thereof, said seams decreasing in depth from ridge to eaves and said channels increasing in depth from ridge to eaves.

12. A car roof comprising roof sheets extending from eaves to eaves and having their adjacent side marginal portions offset upwardly, the upwardly offset side marginal portions of adjacent sheets being lapped for a portion of their width and positively secured together to form hollow upstanding seams that extend from eaves to eaves of the car, the lapped portions of adjacent sheets being offset downwardly on opposite sides of the ridge to form channels in said seams that extend longitudinally thereof, and a member located in said seam and extending longitudinally thereof, said member being positively secured to the downwardly offset lapped portions of the sheets and having upstanding side flanges that project above said lapped portions on opposite sides thereof, said member being of greater width than the width of the sheet lap.

13. A car roof comprising roof sheets ex-

tending from eaves to eaves and having their adjacent side marginal portions offset upwardly, the upwardly offset side marginal portions of adjacent sheets being lapped for 5 a portion of their width and positively secured together to form hollow upstanding seams that extend from eaves to eaves of the car and gradually decrease in depth from ridge to eaves, where they are turned down, 10 the lapped portions of adjacent sheets being offset downwardly on opposite sides of the ridge to form channels in said seams that extend longitudinally thereof, and a member located in said seam and extending longitudinally thereof from side to side of the car, said member being positively secured to the car at the eaves and to the downwardly offset lapped portions of the sheets intermediate the eaves, said member having 15 upstanding side flanges that project above said lapped portions on opposite sides thereof

and gradually increase in depth from ridge to eaves.

14. As an article of manufacture, a car roof sheet, said roof sheet having raised flanges at its side margins whose outer portions are depressed downwardly on each side of the ridge portion of said sheet an amount that gradually increases towards the eaves 25 portions of said sheet.

15. As an article of manufacture, a car roof sheet, said roof sheet having raised flanges at its side margins whose outer portions are depressed downwardly on each side of the ridge portion of said sheet an amount 30 that gradually increases towards the eaves portions of said sheet, where the downwardly offset portion lies substantially in the plane of the body of the sheet.

Signed at New Kensington, Pennsylvania, 40
this 26th day of April, 1924.

CHARLES DAVID BONSALL.
